UNITED STATES PATENT OFFICE.

CHARLES L. CLARKE, OF EAST ORANGE, NEW JERSEY.

INSULATING-TUBE FOR ELECTRIC CONDUCTORS.

SPECIFICATION forming part of Letters Patent No. 358,592, dated March 1, 1887.

Application filed July 23, 1886. Serial No. 202,855. (No modcl.)

To all whom it may concern:

Be it known that I, CHARLES L. CLARKE, a citizen of the United States, and a resident of East Orange, in the county of Essex and State 5 of New Jersey, have invented certain new and useful Improvements in Insulating-Tubes for Electric Conductors, of which the following is a specification.

The object of my invention is to provide a 10 separate protective insulating-covering for electric conductors, and which can be slipped over the conductor in those places where the latter is exposed for making joints, or when used for making connections between the different parts of electrical instruments.

In connecting up the various parts of electrical apparatus it is customary, because more convenient, to use naked or imperfectly-insulated wires, and to cover them with short pieces 20 of tubing, in order to protect the conductors, cover the splices, and to prevent electrical connection between the conductors and the metal portions of the apparatus. For this purpose it is customary to employ rubber tubing, which 25 is made for such use and for the trade of various sizes. This tubing is somewhat expensive, and, besides that, it is apt to break or crack when bent around corners of the apparatus upon which it is used, and when the cases of 30 the instrument are of metal, as is frequently the case, false electrical connections are made, and much trouble is thereby experienced. Even though the tubing does not break or crack and expose the conductor when it is first used, 35 yet it is very liable to do so after it has been in use for some time and exposed to the air. Under such circumstances it becomes hard and brittle, and pieces of the rubber will separate from the wire, especially at the points where the 40 insulation is most needed—namely, where the conductor is bent upon the corners of the instrument or when short turns are otherwise made. I have found another difficulty arising from the use of the rubber tubing, which is that 45 when it comes in contact with oil used on the pivots of electrical apparatus it is dissolved and destroyed by the oil, and the wire is left exposed.

My invention is intended to avoid these difficulties by providing a tubing free from these defects, which is as convenient to use as the rubber tubing, and which can be produced at

a lower cost. It consists in forming tubing for the purposes mentioned of braided or woven fibrous or textile material, which may afterward be treated with a suitable insulating substance. The tubing can be manufactured of all the ordinary sizes for the purposes described, and when properly treated with insulating material—such as paraffine—it becomes exceedingly pliable and durable. It can be turned over sharp corners of metal or wood without danger of exposing the conductor or making false contacts between the conductor and the frame of the instrument. An excellent tubing 60 can be made from cotton, jute, or silk, when desired, and I have found by experience that if treated in the ordinary manner with paraffine it remains pliable for an indefinite period, and will not break or crack. The tube may be 65 woven or braided either upon a mandrel, from which it may be afterward removed, or it may be woven upon the mandrel, from which it is removed as fast as it is formed; or other methods of manufacture may be adopted. The tubing 70 may be made either entirely of cotton or other textile fabric, or it may be formed upon the outside of a tubing of rubber or other similar material, in which case all the advantages 75 of the ordinary tubing now in use are obtained, while the latter is fully protected by its external textile covering, and when the latter is treated with paraffine or some other suitable insulating material the inner rubber tubing is 80 fully protected, and its insulating qualities remain practically perfect under circumstances which would destroy the tubing of rubber alone. The outside fibrous covering resists 85 abrasion, will not crack open, and it is difficult to sever it. So far as I have tested the matter I have found that paraffine gives excellent results when used for treating the tubing I have described, and will, I believe, answer all ordinary purposes; but other insulating and preservative substances may be used, as may 90 be found advantageous under different circumstances.

In the accompanying drawings, which illustrate my invention, Figure 1 shows a tube composed of fibrous material, and Fig. 2 shows such a tube with an inner core and which has been slipped over a piece of conducting-wire.

In the drawings, *a* is a short piece of fibrous tubing, woven, braided, or otherwise formed,

and simply treated with paraffine, which permeates the fabric, renders it soft and durable, and gives it the required insulating qualities. 5 *b* is a similar piece, in which the textile fabric is formed upon an interior core or tubing of rubber or similar material.

In very many cases the tubing itself, properly made from ordinary fibrous substances, which, when dry, possess good non-conducting qualities, affords all needed protection and insulation for the wires. The treatment with 10 insulating material and the inner lining of insulating material, as described, give the more thorough protection required for wires when 15 under circumstances of exposure to dampness or other destructive influences.

I do not herein claim a conductor around which an insulating-covering has been woven, braided, or otherwise permanently applied.

20 I claim as my invention—

1. As a new article of manufacture, a flexible tube for receiving electric conductors, braided, woven, or otherwise formed from non-conducting fibrous substances.

2. As a new article of manufacture, a flexible 25 tube for receiving electric conductors, formed by weaving, braiding, or otherwise from non-conducting fibrous substances and having an inner lining of insulating material.

3. As a new article of manufacture, a flexible 30 tube for receiving electric conductors, braided, woven, or otherwise formed from fibrous substances and treated with insulating material.

4. As a new article of manufacture, a flexible tube for receiving electric conductors, braided, 35 woven, or otherwise formed from fibrous substances, treated with insulating material, and having an inner tube or lining composed of insulating material.

In testimony whereof I have hereunto subscribed my name this 21st day of July, A. D. 40 1886.

CHARLES L. CLARKE.
